United States Patent Office

Des. 231,141
Patented Apr. 2, 1974

231,141

PENCIL BOX OR THE LIKE

Herman S. Cripe, 2030 Hillsdale,
Kalamazoo, Mich. 49007

Filed Aug. 27, 1971, Ser. No. 175,809

Term of patent 14 years

Int. Cl. D19—06

U.S. Cl. D74—21 A

The figure of the drawing is a perspective view of a pencil box showing my new design.

I claim:

The ornamental design for a pencil box or the like, substantially as shown and described.

UNITED STATES PATENT OFFICE
CERTIFICATE OF CORRECTION

Patent No. Des. 231,141 Dated April 2, 1974

Inventor(s) Herman S. Cripe

It is certified that error appears in the above-identified patent and that said Letters Patent are hereby corrected as shown below:

The following was omitted from the patent, following the description of the Figure:

-- The design is characterized by the combination of a dark top panel, a contrasting light band around the base, and a band of vertical stripes of varying hues of colors around the lateral surfaces of the pencil box or the like above the base, all as shown in the drawing. --

Signed and sealed this 1st day of October 1974.

(SEAL)
